RELAY

Frederick J. Marco, Carl G. Anderson, and Folke A. Brandstrom, Chicago, Ill., assignors to Comar Electric Co., Chicago, Ill., a corporation of Illinois

Application September 28, 1940, Serial No. 358,790

1 Claim. (Cl. 175—336)

This invention relates to electrical equipment in the nature of a relay, one of the principal objects being the provision of a device of this class which is simple and rugged in construction and characterized by an increased efficiency in both electrical and mechanical operation.

One of the specific objects is the provision of an improved non-magnetic mounting for the armature by means of which the armature may be caused to release quickly when the coil is de-energized.

Another object is the provision of an improved non-magnetic stop for the armature which constitutes a part of the non-magnetic armature mounting.

A further and important object is the provision of a non-magnetic fulcrum or rocking seat for the armature and means on the armature and seat providing an interlocking connection between these parts by means of which the armature is mounted for free movement but is prevented from excessive wobbling or disengagement from its seat.

Still another object is the provision of a non-magnetic seat or fulcrum for the armature which is attached removably by means of a single screw by means of which the armature may be removed without disturbing the relay switches.

Another highly important object is the provision of improved mounting means for the entire relay, said means including the provision of a recessed part on the field piece or frame, and into which the lower part of the core projects for engagement with a retaining collar or nut, said collar or nut being entirely disposed within said recessed part so that the latter can lie flushed on a mounting surface, the portion of the core which is engaged in said recess and nut being tapped to receive a mounting screw by means of which the relay is disposed in operative position.

Still another object is the provision of an improved phase-splitting or pole-shading ring which is characterized by the provision of opposite wings or projections adapted to prevent the header-washer from coming off the pole piece or core.

Other objects, advantages and novel aspects of the invention reside in certain details of construction as well as the cooperative relationship of the component parts of the illustrative embodiment described hereafter in view of the annexed drawing, in which:

Fig. 1 is a side elevation of the improved relay with portions shown in vertical section.

Fig. 2 is a rear elevation of the relay with portions of the switch spring shown in section.

Fig. 3 is a horizontal section along line 3—3 of Fig. 1 showing the phase-splitting ring in plan.

Fig. 4 is a vertical sectional detail along lines 4—4 of Fig. 1 showing the accommodation washer.

Fig. 5 is a fragmentary exploded view of the 10 armature and insulated pusher member.

By way of general introduction it is stated that relays of the type hereinafter described include a movable magnetically attractable member known as the armature, together with a frame or 15 field piece of magnetic material upon which the armature is movably or rockably seated. The movable element or armature usually operates some kind of a switch also forming part of the relay, and the device is completed by the provision of a winding through which an electric 20 current is passed to magnetize a core member therein and set up a magnetic circuit through the frame or field piece and the armature and cause the armature to be attracted from a normal position toward the core.

The armature is usually held in its normal position by a spring, and the electric current which must magnetize the armature to attract it must overcome the resistance of this spring as 30 well as the resistance resulting from the operation of said switch.

These relays must operate quickly and positively both in releasing and in pulling up, and large numbers of these relays must be available to operate on low voltages or with a fairly low magnetizing current. In view of these facts, it will be apparent that the spring tension for the armature spring, as well as the resistance of the 35 associated switch means, must be kept low if the armature is to do its work satisfactorily.

A peculiarity of the magnetic circuit set up in the relay is the marked tendency of the magnetic force to continue in effect a short time after energizing current has been shut off. In order to 45 overcome this sticking tendency the armature springs are commonly made relatively strong; but it will be apparent that there is a limit to the application of this expediency where the relay must operate on a low current. It therefore becomes necessary to provide a means for quickly causing the magnetic force to become dissipated. One of the known methods for accomplishing this is by inserting a non-magnetic 50 material in the magnetic circuit, for example, at

a point between the connection of the armature with the field piece or frame.

According to the present invention, such a break in the magnetic circuit is achieved by providing a non-magnetic seat or fulcrum on the field piece or frame and upon which the armature is mounted for rocking movement.

Referring to Fig. 1 the improved relay includes the frame or field piece generally indicated at 10, there being a vertical section 11 and a lower horizontal foot section 12 by means of which the relay is mounted on a supporting rack or surface. At the upper end of the field piece is an opposite horizontal projection or switch mounting shelf 13. The frame or field piece 11-12-13 is constructed of a magnetic material such as iron.

Mounted upon the shelf 13 is a simple variety of spring leaf switch including a plurality of switch blades 14-15-16, secured between a plurality of insulating blocks 17 held in assembled relation by screws 18 engaged in the shelf. As seen in Fig. 4 particularly, the switch assembly is prevented from rattling loose by the provision of an arcuate accommodation washer 19. This washer is a piece of spring metal which has been bent into arcuate shape along its length so that its outer edges 20 bear against the upper surface of the topmost one of the insulating blocks 17, while leaving a space 21 around the screw 18 to accommodate the upper protruding end of an insulating sleeve 22. In this way, the screws 18 may be turned up tightly notwithstanding the accidental protrusion of the upper end portions of the sleeve 22.

The improved armature 23 is shown in perspective in Fig. 5, and as seen also in Fig. 1, includes a pusher 24 of insulating material provided with a notch 25 which fits around the notched part 26 adjoining a vertical upset lug 27 at the front of the armature, the pusher being rigidly secured to lug 27 by means of a rivet 28.

The pusher 24 is provided with a horizontal slot 24a into which the end portion 15a of certain of the switch blades project to be flexed by movement of the armature from its normal position, shown in Fig. 1, when the coil 29 is energized.

Armature 23 is mounted at its right-hand end on a non-magnetic fulcrum or seat 30. The member 30 is preferably constructed of brass or some other suitable non-magnetic metal, and is provided with opposite punches 31 fitting into holes or recesses 32 in the underlying portion of the vertical leg 11 of the field piece, upon which the seat or fulcrum is removably secured by means of a single screw 33.

The upper edge of the brass seat or fulcrum is slotted as at 34 to accommodate the opposite side wings 36, which are adjacent the tail 37 of the armature. The tail 37 projects through the central slot 35 in the seat or fulcrum and connects with the upper hooked end 38 of the normal spring 39.

The portions 30a of the brass seat or fulcrum (resulting from the formation of slots 34, 35) project upwardly into the slots 36a made in forming the side wings 36 on the armature, and in this manner may be said to interlock with the armature, there being a sufficient clearance between the projections 30a and the wing slots 36a to permit the armature to rock in free vertical movement on its seat.

It should be observed that in the mounting of 75

the seat or fulcrum 30 on the vertical leg 11 of the field piece (Fig. 1), there has been provided a clearance 40 between the cut-away portions 41 on the vertical leg 11 by means of which the armature is passed into engagement with seat 30. This clearance 40 is as slight as possible to prevent any chance of actual contact between the armature and the field piece while at the same time minimizing the clearance to reduce 10 the reluctance of the magnetic circuit.

In order to secure this armature in its seat, there is provided a retaining member or keeper 45, also constructed of a non-magnetic material such as brass and secured to the vertical leg 11 15 as by rivets 46. The lower edge portion of this keeper is disposed closely opposite the upper edge portion of the projections 30a on the seat whereby displacement of the armature from the latter is effectively prevented.

20 A feature of the foregoing keeper structure is the provision of a stop arm projection 47 which is bent over from the part 45 and projects through a slot 48 in the field piece 11 with an offset stop portion 49 disposed above the armature 25 to limit the upward movement of the latter under influence of the spring 39.

25 A further important feature of the invention resides in the provision of improved mounting means for the coil 29 and for the relay as an 30 entirety. As seen in Fig. 1 the horizontal "foot" portion 12 of the frame or field piece is offset as at 12a to provide a recess 12b into which projects the lower end portion 50 of the pole piece or core of the winding 29. The portion 50 is 35 threaded exteriorly and also tapped to receive, respectively, an attaching nut 51 which fits snugly into the recess 12b and holds the magnet or winding 29 on the foot, and a mounting screw 52 threaded into the core through a mounting 40 member 53 whereby the entire relay unit is secured in operative position. A positioning lug 12c is provided at the end of the foot 12 to engage in a recess in the mounting member 53 and prevent the relay from rotating or working 45 loose on its mounting. Heretofore the core has been staked or peened onto the frame, a method which caused frequent injury to the winding, and which prevents removal and substitution of coils.

50 Another feature of the invention is illustrated in Fig. 3 wherein the shading piece or phase-splitter is shown as a substantially circular member of copper or other highly conductive non-magnetic material with a central opening 55 across which projects a bar or web 61.

The upper end of the core 50 of the magnet is 60 cross-slotted as at 62 leaving two pole faces 63 to project through the disc 60 on opposite sides of the cross-bar or web 61. The provision of such shading rings, is not new, its purpose being to prevent complete collapse of the magnetic field during current changes on an alternating current circuit, whereby to eliminate objectionable humming and chatter of the armature. 65 However, the new feature of this shading ring resides in the provision of opposite wings 64 projecting toward each other somewhat beyond the cross web 61. These wings 64 prevent the top washer or header 65 from working loose, especially when the wire is wound on to the spool or core in making the magnet.

70 It is to be understood that in order for the phase-splitting washer or slug 60 to do its intended work, it cannot extend entirely around the pole faces 63; however, we have found that

the wings 64 may be extended substantially the amount illustrated without interfering with the efficiency of the shading piece or slug, while at the same time preventing working loose of the header washer.

The foregoing novel features all contribute to the production of a highly efficient relay, both electrically and mechanically without substantially increasing the relative cost of production of such a device. The novel combination stop and keeper 45-49, and the co-operating seat or fulcrum 30 provides an efficient and rugged means for removably mounting the armature for maximum efficiency as regards the magnetic circuit, while at the same time providing a sufficient break in said circuit to assure positive release of the armature from operated condition when the current is interrupted; and further for removing the armature without disturbing the relay switches or switchstacks. The wing projections on the shading slug permit the wire to be wound tightly on the core without danger of loosening the top header washer 65, and the recessed mounting of the lower end of the core securely fixes the coil on the frame.

The preferred embodiment of the invention set forth herein has been described in detail for purposes of illustration, it being understood that the objects of the invention may be accomplished by other forms and arrangements of the specific means set forth, so that the invention is not to

be limited to any precise details of form, location, or function except as may be provided hereinafter in the appended claim.

We claim:

5. In a relay of the type having an upright frame member with an armature projecting horizontally therefrom and a switchstack supported on a part of said frame member in approximate parallelism with said armature, improvements comprising: a non-magnetic fulcrum piece removably attached to said frame member beneath said armature with said armature rocking entirely on the fulcrum piece and having interfitting engagement with the latter; a non-magnetic stop and keeper attached to said frame member separately from, and beneath, said switchstack with keeper portions closely overlying said armature and in alignment with said fulcrum piece, whereby the armature is kept from dislodgement, said stop and keeper including a stop portion projecting over said armature to limit upward motion thereof in rocking movement, said fulcrum piece being removable as aforesaid to provide for removal of the armature
